Term of patent 14 years

(Cl. D56—4)

FIG. 4.

FIG. 1.

FIG. 2.

FIG. 3.

FIG. 8.

FIG. 5.

FIG. 6.

FIG. 7.

FIG. 1 is an isometric view of a television receiver or similar article, showing my new design in its turned off carrying position;

FIG. 2 is a side elevational view of FIG. 1 the opposite side being substantially a mirror image thereof;

FIG. 3 is a rear elevational view of FIG. 1;

FIG. 4 is a top plan view of FIG. 1;

FIG. 5 is an isometric view in its turned on stationary state;

FIG. 6 is a side elevational view of FIG. 5, the opposite side being substantially a mirror image thereof;

FIG. 7 is a rear elevational view of FIG. 5; and

FIG. 8 is a top plan view of FIG. 5.

The dominant features of my new design reside in the cabinet, the conventional telescoping antenna being shown in broken lines for illustrative purposes only.

I claim:

The ornamental design for a television receiver or similar article, substantially as shown and described.
